UNITED STATES PATENT OFFICE.

WILLIAM GOLDIE, OF PITTSBURG, PENNSYLVANIA.

DESIGN FOR A TIE-PLATE.

SPECIFICATION forming part of Design No. 31,137, dated July 4, 1899.

Application filed June 12, 1899. Serial No. 720,309. Term of patent 14 years.

To all whom it may concern:

Be it known that I, WILLIAM GOLDIE, a citizen of the United States, residing at Pittsburgh, in the county of Allegheny and State of Pennsylvania, have invented and produced a new and useful Design for a Tie-Plate, of which the following is a specification, reference being had to the accompanying drawing, forming part thereof, which shows a perspective view of the tie-plate embodying the design.

As shown in said drawing, the leading or material feature of my design consists of a tie-plate having its body formed of a thick flat rail-sustaining bar portion *a* and two depending flanges *b* below such bar portion, one extending along each outer edge thereof, outer thick flat rail-sustaining bar portions *c*, thin webs *d*, connecting the thick bar portions, and single depending flanges *e* below the outer bar portions *c* and extending along the same.

The plate has also the spike-holes *f*. As so constructed the plate is braced and rendered more rigid by the two depending flanges on the inner thick bar portion which enter the tie and hold thereto. The depending flanges *b* enter the tie longitudinally of the grain of the wood, and the inner bar portion or portions of the plate are braced by the double flanges extending along their lower edges.

What I claim as new, and desire to secure by Letters Patent, is—

The design for a tie-plate as herein shown and described.

In testimony whereof I, the said WILLIAM GOLDIE, have hereunto set my hand.

WILLIAM GOLDIE.
